UNITED STATES PATENT OFFICE.

WILLIAM W. BYAM, OF CHICAGO, ILLINOIS, ASSIGNOR TO BYAM TIRE AND RIM COMPANY, A CORPORATION OF ILLINOIS.

WHEEL.

1,127,729.

Specification of Letters Patent.

Patented Feb. 9, 1915.

Application filed February 13, 1912. Serial No. 677,384.

To all whom it may concern:

Be it known that I, WILLIAM W. BYAM, a citizen of the United States, residing at Chicago, in the county of Cook and State of Illinois, have invented certain new and useful Improvements in Wheels, of which the following is a specification.

The object of my invention is to provide certain improvements in tire fastening devices of the form set forth in my prior applications for United States Patents Serial Nos. 597,934, filed December 17, 1910, 636,426, filed July 1, 1911, and 653,165, filed October 17, 1911. In all of these applications I have described and claimed means for fastening a resilient tire to a rigid base or rim, said means being characterized by a projection or boss on the inner face or basal portion of the tire coating with a depression in the rigid base or rim, an anchor embedded in the interior of the tire opposite said boss, a stem engaging the anchor and rigid base or rim, and means for drawing the anchor toward the rigid base or rim to firmly seat the tire thereon.

As set forth in my previous applications referred to, the fastening means is equally applicable whether the tire and rim, or either of them are continuous or made in separate segments, and in the following description and claims I use the word "tire" as including both segmental and continuous tires; although in the preferred embodiment of my invention I make both the tire and rim in separate segments.

The particular object and nature of my invention will clearly appear from the following description and claims, taken in connection with the accompanying drawings, in which

Figure 1 is a side view of half of a wheel to which my invention is applied. Fig. 2 is a sectional view of the structure shown in Fig. 1. Fig. 3 is a fragmentary cross sectional view of the outer part of a wheel showing one of the bolts which hold the tire and segmental rim upon the inner part of the wheel. Fig. 4 is a view similar to Fig. 3, but showing a bolt which secures the tire to the rim and acts as a dowel between the rim and inner part of the wheel. Fig. 5 is a circumferential section in the plane of the wheel showing the forms of bolts illustrated in Figs. 3 and 4. Fig. 6 is a perspective view of one of the anchors, the

anchor shown in this view being separable from the stem of the bolt and adapted to have a screw threaded engagement therewith. Fig. 7 is a perspective view of an anchor made integral with the stem of the bolt, the anchor being also provided with dowels adapted to project inwardly from the tire and to engage apertures in the outer part of the wheel or felly band. Figs. 8, 9 and 10 are perspective views of rim segments consisting of one, two and three units, respectively, Fig. 8 showing side flanges upon the rim segment adapted to engage the sides of the felly band. Fig. 11 is a view showing a form of construction of integral rim sections which may be used for wide tread wheels. Fig. 12 is a cross section through an integral rim section comprising three units, the tire and felly being also shown. This section is on the line 11-11 of Fig. 13. Fig. 13 is a diagrammatic view of a rim and tire section comprising three units. Fig. 14 is a fragmentary perspective view of part of a felly band. Figs. 15 and 16 are views of bolts or screws used in the multiple rim sections. Fig. 17 is a fragmentary perspective view of a tire and outer part of a wheel, showing the application of my improved fastening device in connection with a continuous rim, the tire being either segmental. In this view I also show a plurality of anchors in the base of each segment when the tire is segmental, and if the tire is made continuous there will be a plurality of rows of anchors extending around the circumference. Fig. 18 shows the relation of the tire and rim before the screws or bolts are applied. Fig. 19 is a view of the inner side of two rim segments. Fig. 20 shows a circular anchor in which no provision is made for securing a large extent of surface normal to the base of the tire and to the rim. Fig. 21 is a central longitudinal section through the structure shown in Fig. 8. Fig. 22 shows an anchor which projects above the walls of the depression in the rim.

I will first describe the anchor by which the resilient tire is secured to the rim. This anchor is similar in its principle of operation and general form to that described in my prior applications and is adapted for use with segmental or continuous tires and rims.

In the particular form illustrated in Fig.

6, the anchor 1 is provided with a plurality of arms 2 radiating from a central hub 3, which is provided with a screw-threaded opening 4 adapted to be engaged by the stem 5 of a bolt or screw. The anchors are molded and vulcanized into the base of the tire, the arms of the anchor preferably being first wrapped with fabric 5 impregnated with rubber or other suitable material to insure 10 a secure connection between the anchors and the rubber of which the tire is formed. Preferably a layer of fabric 6 is also molded into the base of the tire inside of the anchors. The inside of the tire opposite 15 the anchors preferably takes the form of a boss with inwardly converging sides. The entire base of each segment may take the form of a single boss having an anchor embedded therein, or each segment may be provided 20 with a plurality of bosses and anchors as indicated in Fig. 17. The arms of the spider anchors are flattened or oblate in cross section and are made of considerable depth in a direction normal to the periphery of the wheel in order to present large 25 surfaces 10.

Referring to Fig. 3, it will be apparent that in the assembled structure tangential or side strains upon the tire are resolved at 30 the inner part or base of the tire into an outward radial pull tending to separate the tire from the rim. The large surfaces 10 upon the anchor arms lie in the planes in which the forces due to tangential and side 35 strains act, and these forces therefore are exerted in line with the joint between the surfaces 10 of the arms 2 and the webbing 5 and rubber of which the tire is formed. By this arrangement the joint between the 40 arms 2 and the material of the tire offers the maximum resistance to the strains imposed upon it.

While I have illustrated and described an anchor consisting of a central hub and radiating arms the anchors may be otherwise formed. The radiating arms illustrated form what may be termed a grid and present a large extent of side surface 10, but it will be obvious that the members forming 45 the anchor may be so disposed as to make a grid of different form while still presenting the desired amount of side surface substantially normal to the base of the tire. Furthermore, the anchors molded into the tire 50 and disposed with relation to the rim as herein described possess advantages independent of the precise form of the anchors.

As illustrated in Fig. 7, the anchors may be provided with lugs or dowels 11, designed in the completed and assembled structure to project inwardly through and beyond the material of the tire and to be received in openings 12 which are formed in the rim, as shown in Fig. 8, when this form 55 of anchor is used. The purpose of the dow-

els 11 when employed is to assist in securing the anchors and tire against sidewise or tangential displacement. I have found, however, that these dowels may ordinarily be dispensed with.

The bosses at the base of the tire are preferably constructed of less depth than the depressions in the rim, as shown in Fig. 18, thereby necessitating the application of some force to seat the tire in the position shown in Fig. 3. The force necessary to seat the tire upon the rim is applied through the medium of bolts or screws such as illustrated in Figs. 3, 4, 15 and 16. The bolts 7 serve to hold the tire upon the rim, to hold the rim upon the wheel, and to act as a dowel between the anchor, rim and wheel preventing relative side or tangential movement. The screws or bolts 8 serve to hold the tire upon the rim and they are provided with heads 14 which engage the openings 15 in the felly band 16 for the purpose of doweling or keying the tire and rim to the wheel. The screws or bolts 13 serve only to hold the tire to the rim. The different uses of 85 the bolts 7, 8 and 13 will be described below. The rim, *i. e.*, the rigid base member to which the tire, whether continuous or segmental, is secured, may either be continuous or consist of a plurality of separate sections, 90 or segments. When the rim consists of separate sections, each section may be made of a circumferential length of 3.1416 inches or some multiple or aliquot part thereof in order that they may be accurately fitted to 95 wheels whose external diameter is an integral number of inches. In the preferred construction both the tire and rim are made in separate segments. Some or all of the rim segments, however, may comprise a 100 plurality of units, *i. e.*, may contain cavities or depressions for more than one tire segment or for more than one of the bosses of a longer tire section or continuous tire.

In Figs. 8, 9 and 10, I have shown single, 110 double and triple segments, comprising one, two and three units respectively and adapted to receive one, two and three tire segments respectively. In the form shown in Fig. 8, the rim segment is provided with side flanges 40 which in the assembled structure embrace the sides of the felly band 41 for the purpose of contributing to the rigidity of the connection between the rim and wheel. These side flanges may not in all 115 cases be necessary. In Figs. 1 and 2, I have shown the tire and rim segments contacting with each other, but while the circumferential length of the segments may be adapted to form a continuous series around 120 wheels the diameters of which are an integral number of inches, it will be obvious that my improved tire and rim segments when constructed of any dimensions desirable may be mounted with intervening 125 130

- spaces between the tire segments for the purpose of securing greater traction and also securing additional ventilation to cool the tire.
- 5 For wheels having comparatively narrow treads, the rim segments are formed as shown in Figs. 8, 9 and 10, those illustrated being adapted to receive one, two and three tire segments respectively. The rim segments are formed with depressions 17 surrounded by inwardly converging walls 18. The upper edges of the walls 18 are preferably formed with a shoulder 19 as clearly shown in Figs. 3, 4 and 18 or with a groove 15 42 as shown in Fig. 12, and the bosses upon the inside of the tire are preferably so formed that a higher degree of pressure is set up between these shoulders or grooves and the tire than elsewhere. The position 20 of the tire before being seated in the rim is shown in Fig. 18 and its position after being so seated is shown in Figs. 3, 4 and other views, from which it will be apparent that the forcible seating of the tire on the 25 rim has the effect of setting up a high degree of pressure at the edges of the depressions 17 in the rim. Each of the rim segments is provided at each end with projecting lugs and with overhanging shoulders, the projection 21 at one end of each segment being opposite the overhanging shoulder 22 at the opposite end of the same segment and the overhanging shoulders 20 at the first mentioned end of the segment 30 being opposite the projections 23 at the opposite end. The projections and overhanging shoulders are arranged in the same relation on all of the segments, and in the assembled structure the projections 23 and 21 35 lie inside of the overhanging shoulders 20 and 22 respectively. The rim segments are provided with perforations in the base of the depressions 17 to receive the bolts 7, 13 or 8 as the case may be. The bolts 7 are 40 necessary to secure the segmental rim to the wheel, but it is not necessary that such bolts be used in all of the perforations 24 and in some cases, as, for instance, where a spoke 45 would interfere with the use of the bolts 7, such bolts may be omitted from part of a rim segment, or if necessary from an entire rim segment, such segments being held in place by the engagement of its projections 21 and 23 with the adjacent bolt held segments. By constructing the rim in multiple segments containing two and three units, it is possible, by a proper selection of the segments to dispose the bolts 7 advantageously 50 regardless of the disposition of the spokes in the wheel to which the rim is applied.
- In those instances in which the bolts 7 are not used the tire may be secured to the rim by means of either the short bolts 8 or 13, the bolts 8 being used when it is desirable 55 to dowel the rim to the wheel. In the case of multiple segments, such as illustrated in Figs. 9 and 10, I prefer, on account of their greater length, to construct them upon an arc of the radius of the wheel to which they are to be applied in order to accurately 60 preserve the circular form of the outer periphery of the tire, but the single or unit segments shown in Fig. 8 may be applied to wheels of any diameter within the limits ordinarily used. In order to facilitate the 65 application of the single rim segments to wheels of different diameters, I construct the ends in the form of narrow flanges 40, and recess the central part of the under side of the segments as indicated at 41. As the 70 edges of the flanges 40 are comparatively narrow they will fit with substantial accuracy upon wheels of any of the diameters in ordinary use.
- With wheels having a wide tread, I may 75 apply my invention as illustrated in Figs. 11 to 14. In Fig. 11, I illustrate an integral rim section or segment comprising six units designated by the numerals 25 to 30, and intended for use in mounting three peripheral rows of tire segments upon a wheel. The segments extend in continuous rows 80 around the wheel, but are staggered side-wise, *i. e.*, the segments of the upper, middle and lower rows indicated in Fig. 10 break 85 joints, the joints in one row lying opposite the center of the segments in the next row. In Fig. 13, I have illustrated diagrammatically a rim segment comprising three units 90 and designed for use in applying two or 100 more rows of tire segments to a wheel. The segments of multiple width, such as shown in Figs. 11, 12 and 13, may be provided with depending side flanges 31 adapted to lie 105 outside of the felly band as shown for the purpose of restraining the rim members against sidewise movement. The depending side flanges 31 may, however, be omitted. Wheels having wide treads may also be fitted with rims of the form shown in Figs. 8, 110 9 and 10, the segments being arranged in a plurality of circumferential rows.
- In Fig. 17 I have illustrated the application of my tire fastening device to a continuous rim 45, *i. e.*, a rim which extends 115 completely around the wheel as distinguished from a rim composed of a plurality of separate segments, and in connection therewith have shown means for mounting such a rim upon a wheel. Inasmuch as the 120 means for mounting the rim 45 shown in Fig. 17 upon the wheel forms no part of the invention claimed herein description thereof is unnecessary. In Fig. 17 I have shown in solid lines a continuous tire, but a tire 125 divided into segments upon the dotted lines could be substituted for the continuous tire. The construction shown in Fig. 17 embodies the idea of providing two circumferential rows of depressions or cavities in the rim, 130

and in the application of a segmental tire to such a rim, as indicated in dotted lines, each segment would be provided with four bosses and four anchors. It will be understood that my invention is not limited to any particular form or arrangement of the anchors and bosses other than as defined in the following claims.

In Fig. 20 I show an anchor 50 of circular form and having no provision for a large extent of surface normal to the base of the tire. While this form of anchor does not embody the form and disposition of the joint between the anchor and tire material which I prefer, it possesses the other advantages of my invention.

Fig. 22 represents a tire and rim together, with an anchor having radiating arms 51, but in this construction the anchor projects outward beyond the walls of the depression in the rim and beyond the webbing at the base of the tire. For some distance outward beyond the walls of the rim depressions the conditions vary but little from the conditions within the depressions, and in some instances the structure shown in Fig. 22 may be resorted to.

I claim:

1. In combination, a rim, a resilient tire, anchors molded into the interior of said tire and having stems engaging said rim, bosses projecting inwardly from said tire and surrounding said stems, said rim having depressions surrounding said stems opposite said bosses, and means for drawing said anchors inwardly thereby forcing said bosses into firm engagement with said rim, said anchors in the assembled structure being surrounded by the outwardly projecting walls of said depressions.
2. In combination, a rim, a resilient tire, anchors molded into the interior of said tire and having stems engaging said rim, bosses projecting inwardly from said tire and surrounding said stems, said rim having depressions surrounding said stems opposite said bosses, said bosses normally not extending to the bases of said depressions, and means for drawing said anchors inwardly thereby forcing said bosses into firm engagement with the bases of said depressions, said anchors in the assembled structure being surrounded by the outwardly projecting walls of said depressions.
3. In combination, a rim having depressions in its peripheral surface, a resilient tire having bosses on its inner surface registering with said depressions, anchors engaging the interior of said tire and having stems extending inward through said bosses and engaging said rim, and means for drawing said anchors inward, said anchors in the assembled structure lying in the rigid pockets formed by the walls of the depressions in said rim.

4. In combination, a rim, a tire comprising an outer resilient zone and an inner zone of webbing, said tire having bosses projecting from its inner surface, anchors engaging the interior of said tire and having stems extending inward through said bosses and engaging said rim, depressions in said rim opposite said bosses, means for drawing said anchors inwardly to hold the inner surface of said tire against said rim, said anchors when so drawn inward lying in the rigid pockets formed by the walls of the depressions in said rim and the webbing forming the inner zone of said tire.

5. In combination, a rim having in its outer surface a plurality of depressions, each depression being surrounded by an outwardly extending wall, a resilient tire having a plurality of projecting basal portions normally contacting with the upper portions of said walls and extending into said depressions but being normally spaced from the floors thereof, anchors embedded in said basal portions, and means engaging said anchors and rim for drawing said basal portions into said depressions and securing said tire to said rim, the joint between said anchors and the resilient material of said tire being protected in the assembled structure by the surrounding walls of said depressions.

6. In combination, a wheel rim having in its outer surface a plurality of depressions, each depression being surrounded by an outwardly extending wall, a resilient tire having a plurality of basal portions seated in said depressions, anchors embedded in said basal portions, and means engaging said anchors and rim for securing said tire to said rim, the joint between said anchors and the resilient material of said tire being protected in the assembled structure by the surrounding walls of said depressions.

7. A resilient tire, a wheel, anchors embedded in said tire, said anchors lying in planes substantially parallel to the peripheral surface of the rim of said wheel, said anchors being formed of a plurality of members separated by spaces into which the material of the tire extends, said members being relatively thin in a direction parallel to the peripheral surface of the rim and of relatively great depth in a direction normal thereto, whereby the greater part of the adjoining surfaces of said anchors and tire lies in planes substantially perpendicular to the base of the tire, and means for securing said anchors to the wheel felly.

8. In a device of the class described, a wheel rim having depressions in its outer face, a tire having bosses or projections on its inner face adapted to be seated in said depressions, anchors embedded in said tire opposite said bosses, said anchors being formed of a plurality of members separated

- by spaces into which the material of the tire extends, said members being relatively thin in a direction parallel to the peripheral surface of the rim and of relatively great depth
- 5 in a direction normal thereto, whereby the greater part of the adjoining surfaces of said anchors and tire lies in planes substantially perpendicular to the base of the tire.
9. In a device of the class described, a rim
- 10 having depressions in its outer surface the walls of said depressions converging toward the floors thereof, a resilient tire having basal portions adapted to seat in said depressions but normally not extending to the
- 15 floors thereof, anchors embedded in the basal portions of said tire, each of said anchors
- having a plurality of members separated by spaces into which the material of the tire extends, said anchors lying adjacent the inner periphery of the tire and having a contour upon their inwardly facing sides similar to but slightly smaller than said depressions, and means for drawing said anchors inwardly thereby closely and forcibly seating the basal portion of the tire in said depressions.
- 20
- 25
- In testimony whereof, I have subscribed my name.
- WILLIAM W. BYAM.
